(57) **CLAIM**

The ornamental design for a docking station for compression devices, as shown and described.

DESCRIPTION

FIG. 1 is a right perspective view of a design for a docking station for compression devices.

FIG. 2 is a right perspective view of the design shown in FIG. 1 with compression devices supported thereon shown in phantom.

FIG. 3 is a right perspective view of the design shown in FIG. 1 with the lid of the docking station open and one of two batteries disposed within the docking station.

FIG. 4 is a right perspective view of the design shown in FIG. 1 with the lid of the docking station open and both batteries of the claimed design, one disposed within the docking station and one being inserted into the docking station.

FIG. 5 is a front elevational view of the design shown in FIG. 1.

FIG. 6 is a rear elevational view of the design shown in FIG. 1.

FIG. 7 is a right side elevational view of the design shown in FIG. 1.

FIG. 8 is a left side elevational view of the design shown in FIG. 1.

FIG. 9 is a bottom elevational view of the design shown in FIG. 1; and,

FIG. 10 is a top elevational view of the design shown in FIG. 1.

The broken lines seen in FIGS. 2 and 4 show environmental structure associated with the docking station for compression devices in a condition of use. The broken lines and structures they depict form no part of the claimed design.

1 Claim, 9 Drawing Sheets
